DISPENSER FOR SHEET MATERIAL ON A ROLL

Livingston C. Douglas, Leonia, N.J., assignor to Colgate-Palmolive Company, New York, N.Y.

Filed July 29, 1974, Ser. No. 492,799

Term of patent 14 years

Int. Cl. D23—02

U.S. Cl. D6—96

FIG. 1

FIG. 2

FIG. 3

FIG. 4

FIG. 5

FIG. 1 is a front elevation of a dispenser for sheet material on a roll embodying my new design;

FIG. 2 is a bottom plan view thereof;

FIG. 3 is a top plan view thereof;

FIG. 4 is a right side elevation thereof, the left side being similar; and

FIG. 5 is an elevation taken in the direction indicated by line 5—5 of FIG. 4.

I claim:

The ornamental design for a dispenser for sheet material on a roll, as shown and described.
